Albert D. Grudd

United States Patent Office.

ALBERT D. JUDD, OF NEW HAVEN, CONNECTICUT.

Design No. 4,077, dated May 31, 1870.

DESIGN FOR A METALLIC BRACKET.

The Schedule referred to in these Letters Patent and making part of the same.

To all whom it may concern:

Be it known that I, ALBERT D. JUDD, of New Haven, Connecticut, have invented or produced a new and original Design for a Metallic Bracket; and the following is declared to be a correct description thereof.

This design is adapted to a single metallic bracket, or to a wall-plate for the bracket, either double or single.

I have shown, in the drawing, one side of the wall-plate for a bracket, and a portion of the other side and the edge of the projecting bracket, and a portion of the shelf.

The design of said bracket consists of a circular ornament, *a*, with segmental or arc-shaped bars *b b*, and from the edges of the circular ornament *a* there

are scroll or leaf ornaments, as shown, to connect with the vertical bar *d* and horizontal bar *e* of the bracket.

The edge of the shelf is shown at *f*, with scalloped ornaments around the flanged portion thereof, as shown.

I claim as my invention—

The design of the metallic bracket, as shown and described.

Signed by me this 9th day of April, A. D. 1870.

ALBERT D. JUDD.

Witnesses:

N. F. THOMPSON,
CHARLES IVES.
